ATTORNEY.

UNITED STATES PATENT OFFICE.

EDWARD W. McCANNA, OF ANACONDA, MONTANA.

CRUSHING-ROLL.

SPECIFICATION forming part of Letters Patent No. 661,617, dated November 13, 1900.

Application filed May 11, 1900. Serial No. 16,353. (No model.)

To all whom it may concern:

Be it known that I, EDWARD W. McCANNA, a citizen of the United States, residing at Anaconda, in the county of Deer Lodge and State 5 of Montana, have invented a certain new and useful Improvement in Crushing-Rolls, of which the following is a full, clear, and exact description.

This invention relates to a roll for use in 10 machines for crushing or grinding all kinds of rock and ore; and the object of my invention is to render it unnecessary when renewing or replacing the roll-shells or active surfaces of the roll to take the machine apart. 15

In all machines employing rolls for crushing or grinding the shells wear out and it becomes necessary to replace the worn-out ones with new shells frequently, and as the machines are now constructed it requires considerable time and labor to do this, as the roll and shaft must be lifted out of the bearings, the worn-out shell broken or forced off the core, the new shell fastened on, and the shaft 25 and roll then replaced in the bearings.

In my invention the shell is made in sections, which are held in place on the core by means of clamp-plates bolted to the core, so that the sections can be removed and others 30 substituted without taking the machine apart or lifting the shaft and roll from the bearings, thus saving considerable time and labor.

In the accompanying drawings, illustrating my invention, in both views of which like 35 parts are similarly indicated, Figure 1 is a front view of the sectional shell and core as the roll appears when ready for use. Fig. 2 is a vertical cross-section of the same, showing the manner in which the shell or sections 40 of the same are held firmly in place on the core.

A A are the shell-sections, each of which is made with a dovetailed rib on the inner side adapted to be fitted into a groove in the core. 45

B B are clamp-plates fitting on one side of the core and at one end forming one side of the groove into which the dovetailed rib on the shell fits and at the other end inner end beveled, for a purpose presently appearing.

C is the core, peripherally grooved substantially as shown to receive the ribs of the shell-sections and recessed on one face to receive

the clamp-plates, said recesses being complementary in shape to the adjacent surfaces of the clamp-plates. 55

D D are bolts which fasten the clamp-plates to the core, thus holding the shell-sections in place.

The core C has a hole E, through which the shaft passes, and a keyway F for holding the 60 same in place on the shaft.

It will be observed that the clamp-plates B are applied to one face only of the core and that the core itself is utilized as a complementary fastening and support for the shell-sections A. 65

As shown, the clamp-plates B, in addition to the beveled connection with the shell-sections and core, may have projections at top and bottom to enter corresponding grooves in 70 the shell-sections and core-recess, respectively, in order the more securely to retain the parts in position. It will also be observed that the bolts D extend entirely through the core and that the core and clamp-plates are 75 provided with recesses or countersinks to receive the heads of the bolts and the nuts. It will be observed also that the clamp-plates are equal in number to the number of shell-sections and that their radial lines of division 80 are coincident with the radial lines of division between the shell-sections.

By the construction described of independent clamp-plates and independent shell-sections any of the shell-sections may be removed 85 and replaced without disturbing the others and each and all of the shell-sections may be removed and replaced without dismounting the roll from the machine.

The roll may be made up of as many sections and of any size desired. 90

What I claim is—

1. A roll, for grinding or crushing machines, having a core grooved on its periphery and recessed on one face, and a shell comprising 95 a series of sections each provided with a dovetailed rib to engage the groove in the core, and a complementary series of clamp-plates for said shell-sections constructed to fit the recessed face of the core and to engage the ribs 100 of the shell-sections, and bolted to the core, substantially as described.

2. A roll, for grinding or crushing roll machines, having a dovetailed groove in its pe-

riphery and a recessed face combined with a series of shell-sections having dovetailed ribs to engage the dovetailed groove, and a complementary series of clamp-plates for said shell-sections constructed to engage the dovetailed ribs of the shell-sections and also to engage the recess in the core, and bolts passed through the core and the clamp-plates and thereby independently securing each shell-

section and plate in place and permitting the independent removal and renewal of the shell-sections, substantially as described.

In testimony whereof I have hereunto set my hand this 5th day of May, A. D. 1900.

EDWARD W. McCANNA.
